UNITED STATES PATENT OFFICE.

JOSEPH KEPPLER, OF NEW YORK, N. Y., ASSIGNOR TO BENJAMIN T. B. HYDE, OF NEW YORK, N. Y., TRADING AS HYDE EXPLORING EXPEDITION.

DESIGN FOR A SUPPORT AND UPRIGHT FOR FURNITURE.

SPECIFICATION forming part of Design No. 36,237, dated February 24, 1903.

Application filed January 12, 1903. Serial No. 138,772. Term of patent 7 years.

To all whom it may concern:

Be it known that I, JOSEPH KEPPLER, a citizen of the United States, residing at the city of New York, in the county and State of New York, have invented and produced a new, original, and ornamental Design for a Support and Upright for Furniture, of which the following is a specification, reference being had to the accompanying drawing, forming part hereof, and which is a perspective view of a support and upright, showing my new design.

As illustrated in the drawing, the leading or material feature of my design consists in the configuration or outline of the support and upright, as well as the surface ornamentation thereof. The upright has two end pedestals or legs a, joined by a horizontal rectangular panel b and an arch-shaped panel d, springing from the pedestals a and merging in the horizontal panel b. On each pedestal a is an ornament e in the form of a Katzina or Indian god, and each pedestal a conventionally outlines the head e', arms e'', body e³, and legs and feet e⁴ of the Katzina. The arch d has on its surface the ornaments g and g', respectively, in the form of a Katzina springing from the lower portion of the body e³ of an end pedestal a and abutting head to head, as at g², at the point where the horizontal panel b touches the arch d. Below the head ornaments g² extend the angular panels g³, representing the arms of the curved Katzina ornaments g and g'.

Having thus described my invention, what I claim as new, and desire to secure by Letters Patent, is—

The ornamental design for a support and upright for furniture, substantially as herein shown and described.

In testimony whereof I have hereunto set my signature in the presence of two subscribing witnesses.

JOSEPH KEPPLER.
